UNITED STATES PATENT OFFICE

EDUARD WELTER, OF DRESDEN, GERMANY, ASSIGNOR TO KOCH & STERZEL AKTIEN-
GESELLSCHAFT, OF DRESDEN, GERMANY, A GERMAN COMPANY

HIGH POTENTIAL TRANSFORMER

Application filed July 22, 1930, Serial No. 469,812, and in Germany July 27, 1929.

My invention relates to transformers and particularly to those of the class used in the measurement of high potentials in which the high potential winding comprises a plurality of interconnected coil or disc-shaped windings arranged in the form of a layer or layers surrounding the tubular part of the spool, and has for its object to provide a spool such, for example, as that described in the specification of F. J. Fischer application No. 446,622, filed the 23rd of April 1930, about which the high potential winding, formed independently of the spool and prior to assembly, can be arranged.

A constructional form of the invention is illustrated by way of example in the accompanying drawing.

The spool surrounding the iron core 13 and the secondary winding 14 consists of two insulating bodies 110, 111 which, while being preferably circular, may be of any other desired shape. Each of these bodies is provided at one end with a preferably annular flange 110*, 111* respectively in such manner that when the bodies are telescoped one within the other in the manner shown there is formed a spool for the high potential winding of the usual flanged-end type.

The high potential winding, in the example shown, consists of three layers 112, 113 and 114, each of which comprises a plurality of interconnected coil or disc-shaped windings 115. These individual windings 115 are so arranged and connected in series that complete layer windings are formed, the individual windings of each layer being separated from each other by means of insulating rings 116.

At the end of each of the two outermost winding layers carrying the highest potential there is provided a cap or plate 117 formed as a flange at the end of the respective insulating cylinders 117 separating the winding layers 112, 113, 114. Thus, in this way, the creeping path or "lag" is augmented.

If it is desired to use a transformer having a high potential winding and spool of the type herein specified in cascade the over coupling windings are preferably arranged

in layer-wise formation over the entire length of the spool body, the high potential winding then consisting partly of such layer-wise windings and partly of coil or disc-shaped windings such as 115.

In the example shown the engaging surfaces of the two insulating spool bodies 110, 111 are inclined in such manner that said bodies are wedged together, a secure joint being effected by means of a suitable cementing medium 118. If, however, the surfaces of these bodies are not so inclined but are arranged parallel to the axis of the winding, the bodies may be interconnected by means of screw threads, the "lag" over the securing joint being correspondingly increased. It is also possible to provide a joint between the two insulating members which is partly inclined or stepped and partly threaded.

It will thus be seen that, with a spool of the type above described, the high potential winding may be formed prior to assembling the transformer and, after having been fitted over the body of the outer member 111, the member 110 is telescoped within said outer member and secured thereto as desired, the spool thus formed being, for all practical purposes, unipartite. If the two insulating bodies are formed of suitable material, it is possible, after the winding has been fitted and the joint filled in with cementing medium, to bake said bodies together. Moreover, should said bodies be constructed of porcelain or the like they could be secured with the aid of binding medium such, for example, as china-ware cement.

What I claim and desire to secure by Letters Patent of the United States is:—

1. In a high potential transformer particularly of the class used in the measurement of high potentials, a high potential layer-wise winding, a spool on which said winding is fitted, the winding extending over the entire axial length of the spool in such manner that its potential increases from the outer lying initial potential towards the core surrounded thereby, said spool comprising a pair of preferably tubular members each provided at one end with a flange, said members

being telescoped one within the other to form said spool, their engaging surfaces being secured together.

2. In a high potential transformer particularly of the class used in the measurement of high potentials, a high potential layer-wise winding, a spool on which said winding is fitted, the winding extending over the entire axial length of the spool in such manner that its potential increases from the outer lying initial potential towards the core surrounding thereby, said spool comprising a pair of preferably tubular members each provided at one end with a flange, said members being telescoped one within the other to form said spool, their engaging surfaces being secured together by baking.

3. In a high potential transformer particularly of the class used in the measurement of high potentials, a high potential layer-wise winding, a spool on which said winding is fitted, the winding extending over the entire axial length of the spool in such manner that its potential increases from the outer lying initial potential towards the core surrounded thereby, said spool comprising a pair of preferably tubular members each provided at one end with a flange, said members being telescoped one within the other to form said spool their engaging surfaces being secured together by baking and being inclined with relation to the axis of the high potential winding.

4. In a high potential transformer particularly of the class used in the measurement of high potentials, a high potential layer-wise winding, a spool on which said winding is fitted, the winding extending over the entire axial length of the spool in such manner that its potential increases from the outer lying initial potential towards the core surrounded thereby, said spool comprising a pair of preferably tubular members each provided at one end with a flange, said members being telescoped one within the other to form said spool, and being held in threaded engagement with each other.

5. In a high potential transformer particularly of the class used in the measurement of high potentials, a high potential layer-wise winding, a spool on which said winding is fitted, the winding comprising a plurality of series-connected coil or disc-shaped windings forming layers and extending over the entire axial length of the spool in such manner that its potential increases from the outer lying initial potential towards the core surrounded thereby, a pair of preferably tubular members each provided at one end with a flange, said members being telescoped one within the other to form the spool, their engaging surfaces being secured together as desired.

EDUARD WELTER.
